CAP FOR A FOUNTAIN PEN OR SIMILAR ARTICLE

Joseph Carreiro, Levittown, Pa., assignor to The Esterbrook Pen Company, Camden, N. J., a corporation of New Jersey

Application October 3, 1956, Serial No. 43,210

Term of patent 14 years

(Cl. D74—1)

FIG. 3

FIG. 2

Fig. 1 is a side elevational view of a cap for a fountain pen or similar article made in accordance with my new design;

Fig. 2 is a front elevational view, and

Fig. 3 is a top plan view thereof.

The essential features of my design reside in the portions shown in solid lines on the drawing.

I claim:

The ornamental design for a cap for a fountain pen or similar article, substantially as shown and described.
